Reissue U.S. Appl. No. 11/014,663, filed Dec. 16, 2004, Remmers.

Primary Examiner—Melody N Brown

(74) Attorney, Agent, or Firm—Harness, Dickey & Pierce, P.L.C.

CLAIM

The ornamental design for a hang rod mounting bracket, as shown and described.

DESCRIPTION

FIG. 1 is an upper perspective view of a hang rod mounting bracket, showing my design;

FIG. 2 is a lower perspective view thereof;

FIG. 3 is a left side view thereof;

FIG. 4 is a right side view thereof;

FIG. 5 is a front view thereof;

FIG. 6 is a rear view thereof;

FIG. 7 is a top view thereof; and,

FIG. 8 is a bottom view thereof.

The details shown in broken lines are for illustrative purposes only and form no part of the claimed design.
